Primary Examiner — Marissa J Cash*Assistant Examiner* — Altaira J Swangin(74) Attorney, Agent, or Firm — Tucker Ellis LLP(57) CLAIM

The ornamental design for a spice rack, as shown and described.

DESCRIPTION

FIG. 1 is a top, front, right perspective view of a spice rack showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines show portions of the design that form no part of the claimed design.
